LIQUID-PUMP ARRANGEMENT

Application filed March 31, 1928. Serial No. 98,706.

My invention relates to vacuum distillation of petroleum oil, and more particularly to a novel liquid pump arrangement.

In the oil refining industry it is common practice to vaporize the higher boiling point fractions from crude oil under a high vacuum so that it will not be necessary to heat the crude oil sufficiently to cause an undesirable decomposition or cracking of the molecules of the oil. The vapors thus produced are subsequently condensed under a high vacuum. It is very essential that the vacuum employed be very high, preferably at an absolute pressure of 25 millimeters of mercury or below. It is also quite essential that air leaks into the apparatus be prevented as the air readily combines with or oxidizes the oil with a consequent production of deleterious oxidation products. It is a problem to maintain conditions of high vacuum and exclusion of air in stills, condensers, and associated apparatus employed for this purpose.

It is an object of my invention to provide a novel liquid pump arrangement which removes liquid from a system operated under a vacuum but will absolutely not leak air into the system.

In practice either reciprocating or rotary liquid pumps may be used. All such liquid pumps require stuffing boxes and, since it is very difficult to maintain stuffing boxes gas-tight, there will at times be a leakage of air into the pump which reduces the vacuum in the system and causes oxidation.

It is another object of this invention to provide a liquid pump arrangement having a liquid pump which is submerged in a liquid so that the pump is entirely sealed and can therefore not leak air into the system on which the arrangement is used, this liquid being of such a nature that a small leakage thereof into the pump will not be objectionable.

It is a further object of this invention to provide a liquid pump arrangement of the character mentioned in which said liquid pump discharges the liquid it handles into the body of liquid in which it is submerged, so that said body of liquid will be of the same character as the liquid being pumped.

It is a still further object of this invention

to provide a liquid pump arrangement having a special design of gear pump.

It is a still further object of this invention to provide a liquid pump arrangement of the character specified which requires no stuffing boxes.

Other objects and advantages of this invention will be made evident hereinafter.

Referring to the three drawings in which I illustrate a preferred form of my invention,

Fig. 1 is a partially sectioned view showing an application of my invention.

Fig. 2 is an enlarged sectional view taken through my invention and on the line 2—2 of Fig. 1.

Fig. 3 is a plan view of my invention taken as indicated by lines 3—3 of Figs. 1 and 2.

Fig. 4 is a section taken on the line 4—4 of Fig. 2.

Fig. 5 is a section through the pump proper of my invention and taken on the lines 5—5 of Figs. 1 and 2.

Fig. 6 is a fragmentary view taken on the line 6—6 of Fig. 5.

As shown in Figs. 2 to 6 inclusive of the drawing, my novel form of liquid pump comprises a base 11 having a plate 12 to the lower face of which a flange 13 formed at the upper end of a tank 15 is secured by bolts 17. The tank 15 as shown in Fig. 2 extends downwardly from the base 11, having a cylindrical wall 19 and a bumped bottom 20. An outlet pipe 21 is connected to a cylindrical wall 19 of the tank 15 a considerable distance above the bottom 20, and a drain pipe 23 having a valve 24 is connected with the interior of the tank 15 through the bumped bottom 20. A yoke 26 is supported in the tank 15 by the base 11. This yoke 26 has an upper cylindrical flange 27 which is secured against a lower face of the plate 12 by means of a plurality of stud bolts 28. Extending downward from the flange 27 is a cylindrical wall 29 of the yoke 26, this wall 29 being provided with large openings 30.

A gear pump 34 is secured to the lower end of the yoke 26 near the bottom of the tank 15. The gear pump 34 is provided with a housing 35 having an annular flange 36 through which

cap screws 37 extend for securing the housing to the lower end of the yoke 26, these cap screws 37 extending into a lower part of the yoke 26. Extending downward from an upper wall 39 of the housing 36 is a side wall 40 having a flange 41 formed at the lower end thereof, to which a cover 42 of the gear pump 34 is secured by means of cap screws 43 which extend through the cover 42 and into the flange 41 of the housing 35. The housing 35 of the gear pump 34 is provided with internal gear chambers 44 and 45 which have cylindrical faces 46. Placed in the gear chamber 45 is a drive gear 47 which is rigidly secured on a pump shaft 48 by a key 49. The pump shaft 48 is journaled at its lower end in a socket 50 formed in the cover 42 and extends upward from the pump 34 through a bearing 52 formed in the upper wall 39 of the housing 35. The pump shaft 48 is journaled concentric with the cylindrical face 46 of the chamber 45 and the drive gear 47 is of such a size that the outer faces of the teeth thereof pass extremely close to the face 46 when the gear 47 is rotated. Placed in the chamber 44 is a driven gear 54 which is carried by a shaft 55 supported at its lower end by a socket 56 formed in the cover 42 and at its upper end by a socket 57 formed in the upper wall 39 of the housing 35. The driven gear 54 is of such a size that the outer faces of the teeth thereof pass very close to the cylindrical face 46 of this chamber 44. As shown in Fig. 5 the teeth of the drive and driven gears 47 and 54 mesh 35 at their adjacent sides.

An extension 58 is formed on one side of the housing 35, this extension having an inlet passage 59 which is provided with a threaded and vertically disposed mouth 60, into which the lower end of an inlet pipe or conduit 61 is threaded. An exhaust passage 64 is formed in the housing 35 directly opposite from the inlet passage 59, and has a mouth 65 which opens directly into the tank 15.

As shown in Figs. 2, 3 and 4 the upper end of the pump shaft 48 extends into a socket 68 formed in the lower end of a gear shaft 69. A key 70 is provided at this point for drivably connecting the pump shaft 48 and the gear shaft 69 together. The gear shaft 69 extends upward through a bearing 73 of the base 11. The bearing 73 is made rigid by webs 74 and is preferably provided with a bearing bushing 75. A bevel gear 77 is secured to the upper end of the shaft 69 which projects through the bearing 73 by means of a key 78. The bevel gear 77 is engaged and driven by a pinion gear 80 which is secured on a pinion shaft 81. The left end of the pinion shaft 81 is journaled in a pillow-block 82 secured to a shelf 83 of the base 11 by suitable bolts 84. The right end of the pinion shaft 81 is extended into a connector 85 by means of which it is connected to a motor shaft 86 of a motor 87.

As shown in Figs. 2 and 3 the motor 87 is se-

cured to a table 88 provided by the base 11 by suitable cap screws or bolts 89.

The conduit 61 is provided with a throttle valve 95 which is of any reliable type and which is situated adjacent to the pump 34 and below the outlet pipe 21 of the tank 15. A valve stem 96 extends from the throttle valve proper, upward through the plate 12 of the base 11 and has an operating lever 97 secured to the upper extending end thereof. The valve may thus be readily operated from the exterior of the tank 15.

The conduit 61, as shown in Fig. 1 and merely for the purpose of illustration, is extended to a condenser 100 which is a part of a system of apparatus which is adapted to be operated under a vacuum. This condenser 100 has a cylindrical shell 101 to the opposite ends of which heads 102 are secured. Intermediate partitions or heads 104 are secured inside the shell 101 in a manner to divide the shell into an upper chamber 105, an intermediate cooling space 106 and a lower chamber 107. Extending between the intermediate heads 104 and through the cooling space 106 is a plurality of pipes 108, the passages of which pipes communicate with the upper and lower chambers 105 and 107. A cooling fluid is supplied to and drawn from the cooling space 106 by means of pipes 109.

Vapor to be condensed is supplied to the upper chamber 105 by means of a pipe 111 having a valve 112. The vapor passes downward through the pipes 108 and is condensed, the condensates falling into the lower chamber 107. The uncondensed vapors are drawn from the lower chamber 107 through a pipe 115 by means of a vacuum pump 116 which places a vacuum on the system. The condensates pass through the conduit 61, the throttle valve 95 having been previously opened by an operation of the lever 97, and into the intake passage 59 of the pump 34. The motor 87 at this time is in operation and rotates the pinion shaft 81, which in turn rotates the bevel pinion which engages the bevel gear 77. The bevel gear turns the gear shaft 69 which drives the pump shaft 48. The drive gear 47 is rotated by the pump shaft 48 and by reason of its engagement with the driven gear 54 rotates the driven gear therewith.

The gears 47 and 54 rotate in directions indicated by arrows 120 of Fig. 5. The condensates are carried between the spaces in the teeth of these gears from the intake passage 59 and are delivered to the exhaust passage 64. Since the teeth of the gears mesh at their adjacent sides no liquid can flow therebetween back into the intake passage 59. The principle of operation of the gear pump 34 is identical with that of standard forms of gear pumps. The liquid flows from the exhaust passage 64 into the interior of the tank 15. This liquid fills the tank to a level indicated

at 121 in Fig. 2, which level is determined by the outlet 21.

From the drawings it is obvious that the gear pump 34, which constitutes the liquid pump of the invention, and the throttle valve 95 are entirely submerged in the body of liquid in the tank 15. This liquid provides an absolute seal for the different parts of the pump and for the throttle valve so that it is unnecessary to provide stuffing boxes. Any slight leakage in the pump is readily compensated for by the operation of the gear pump and any slight leakage will not admit air into the pump, but will admit liquid which is of the same character as that liquid being pumped. By discharging the condensates directly into the tank 15, the body of liquid in which the pump is submerged is constantly changing and is always the same as the liquid being pumped. By such provision there will be no contamination of the submerging liquid such as would be the case if a separate sealing liquid, independent of the liquid being pumped, were provided.

The essential feature of my invention is the provision of a liquid pump which is submerged in a body of liquid so that the liquid pump will be sealed by this liquid and so that no air can enter the liquid pump or the system on which the liquid pump is used. The discharging of condensates directly into the tank 15 is also a feature of my invention. A gear pump of the character shown in the drawings readily lends itself to my invention since it is simple in construction, continuous in operation and will require but little attention, and readily compensate for any slight leakage of oil from the tank 15 into the pump 34 which might occur.

The vacuum pump 116 maintains a vacuum in the system and the liquid pump assists inasmuch as it prevents a reverse flow through the pipe 61. The liquid pump will remove only liquid from the chamber 107, and when all the liquid is drawn therefrom it merely functions to keep the air out.

I claim as my invention:

1. In a device of the character described: a tank; a pump supported within said tank; a drive means supported above said pump; connecting means drivably connecting said drive means with said pump, said connecting means extending downward from said drive means to said pump; a conduit connecting to the inlet of said pump, said pump discharging into said tank; and an outlet for said tank arranged to maintain a body of liquid in said tank sufficient to submerge said pump.

2. In a vacuum condensing apparatus the combination of: a container into which liquid is delivered; means for maintaining a vacuum in said container above said liquid; a pipe so connected to said container that said liquid can be withdrawn therethrough;

a pump casing into which said pipe discharges; impelling means within said casing; and a tank surrounding said casing into which liquid from the interior of said casing is discharged, said tank being so constructed that the liquid so discharged submerges all openings in said casing.

3. In a vacuum condensing apparatus, the combination of: a container into which liquid is delivered; means for maintaining a vacuum in said container above said liquid; a pipe so connected to said container that said liquid can be withdrawn therethrough; a pump casing into which said pipe discharges; impelling means within said casing; and a tank surrounding said casing into which the discharge from said pump is allowed to flow, said tank being so constructed that the liquid so discharged submerges all openings in said casing.

4. In a vacuum condensing apparatus the combination of: a container into which liquid is delivered; means for maintaining a vacuum in said container above said liquid; a pipe so connected to said container that said liquid can be withdrawn therethrough; a pump casing into which said pipe discharges; impelling means within said casing; and a tank surrounding said casing into which liquid from the interior of said casing is discharged, said tank being so constructed that the liquid so discharged provides a liquid seal for all openings in said casing.

5. In a device of the character described: a tank; a pump suspended within said tank; a drive means supported above said tank; connecting means drivably connecting said drive means with said pump; a conduit connecting to the inlet of said pump, said pump discharging into said tank; and an outlet for said tank arranged to maintain a body of liquid in said tank sufficient to submerge said pump.

6. In a device of the character described: a tank; a pump suspended within said tank; a drive means supported above said pump; means drivably connecting said drive means with said pump; a conduit connecting to the inlet of said pump, said pump discharging into said tank; and means for maintaining a body of liquid in said tank sufficient to submerge said pump.

7. In a device of the character described: a tank; a pump suspended within said tank; a drive means supported upon said tank above said pump; means drivably connecting said drive means with said pump; a fluid inlet through said tank to said pump; a conduit provided on said pump connecting with said fluid inlet; and an outlet for said tank arranged to constantly maintain a body of liquid therein sufficient to submerge said pump.

8. In combination with a vacuum condensing apparatus having a liquid delivery cham-

ber and a discharge pipe leading therefrom; a pump housing; a tank in which said housing is suspended; impelling means within said housing for discharging liquid from said chamber into said tank; and an outlet for said tank arranged to maintain a body of liquid in said tank sufficient to entirely submerge said housing.

9. In combination with a vacuum condensing apparatus having a liquid delivery chamber and a discharge pipe leading therefrom: a pump housing connected to said pipe for discharging liquid from said chamber; a tank in which said pump housing is suspended; and an impelling means within said housing for discharging liquid from said housing into said tank, said tank having means to maintain a body of liquid therein sufficient to entirely submerge said pump housing.

In testimony whereof, I have hereunto set my hand at Martinez, California, this 20th day of March, 1926.

GUSTAV A. KRAMER
